UNITED STATES PATENT OFFICE.

HERMANN HOPP AND LEO HOPP, OF NEW YORK, N. Y., ASSIGNEES TO HOPP PRESS,
INC., OF NEW YORK, N. Y., A CORPORATION OF NEW YORK.

PRICE CARD OR TICKET.

Application filed June 13, 1925. Serial No. 36,788.

To all whom it may concern:

Be it known that we, HERMANN HOPP and Leo HOPP, both citizens of the United States, residing at the city of New York, county of 5 New York, and State of New York, have invented a certain new and useful Improvement in Price Cards or Tickets, of which the following is a clear, full, and exact description.

10 This invention relates to new and useful improvements in price cards, tickets or the like and it pertains more specifically to a particular construction of price cards or tickets whereby two of such cards may be 15 used together to designate the price of an article in the unit in which said article is ordinarily sold.

The invention contemplates the use of a plurality of cards or tickets which are interchangeable and adapted to be used together in interchangeable relation in order that the same cards may be employed for articles sold in different units.

20 The invention further contemplates means for securing or retaining two of said cards together in order that they may be retained in operative or display position for the purpose intended.

With the above and other objects in view, 30 reference is had to the accompanying drawings, in which:

Figure 1 is a plan view showing two cards and the manner of their use in accordance with the preferred form of the invention;

35 Figure 2 is a transverse, sectional view of the two cards taken on the line 2—2 of Figure 1;

Figures 3 and 4 are plan views showing two different cards of the same type and of 40 the type employed in the preferred form of the invention; and

Figures 5 and 6 are plan views of two different cards of the same general type and illustrating a modified form of the invention.

45 Referring more specifically to the drawings, and particularly to Figures 1 to 4, the reference numeral 10 designates a card. This card has printed thereon a character 11 which in Figure 3 is the numeral 4 and in 50 Figure 4 is the numeral 5. The card 10 is cut transversely along the lines 12, 13 and 14 and it is also cut at right angles to the lines 12, 13 and 14 upon the line 15 which extends from the line 12 to the line 14. This 55 cutting of the cards provides two tabs 16

and 17, each of which is printed or otherwise provided with characters 18. These characters 18 are in the case of the tab 16 the word "For" and in the case of the tab 17, the legend "Lbs". These tabs 16 and 17 60 are adapted to fold upon the dotted line 19 so that either one or both of them may be folded to a point where they occupy a position in spaced relation with respect to the body portion of the card or ticket 10. 65

The reference numeral 25 designates a second card and said second card is provided with characters 26 which in the present instance is 14 and associated with said characters 26, there is a designating character 27 70 which in the present instance is the character "¢" used for designating "cents".

The cards or tickets are adapted to be used in the following manner.

Assuming that it is desired to display the 75 price of a commodity, for example, salt, the sale price of which would be 4 pounds for 14¢, the ticket 25 would then be inserted under both of the tabs 16 and 17 as shown in Figure 2. The display would then read: "4 80 lbs. for 14¢. If desired, however, the card 25 may be placed under only the tab 17 in such a position as to obscure the tab 16 in which position the legend would read: 4 85 lbs. 14¢, as shown in Figure 1. It is obvious that the two cards may be used in either manner.

Assuming now, that the article on which it is desired to display a price is sold as an article rather than in the unit of pounds, if 90 now, the card 25 is placed beneath the tab 16 with the tab 17 obscured by the upper edge of the card 25, it will be obvious that the legend then will read: 4 for 14¢.

By employing cards 10 which are printed 95 with various characters 11 and cards 25 which are printed with various characters 26, it is obvious that any two of these cards may be used together as shown in Figure 1 for the purpose of displaying a number of 100 articles, which will be sold for a given price or the number of units of the article which will be sold for a given price.

In that form of the invention shown in Figures 5 and 6, the cards 30 are divided in 105 one direction into two areas 31 and 32, it being understood that this is done on the opposite faces of the card. Each of these cards is cut out as described heretofore to provide tabs 33 and 34 which tabs carry the 110

characters "For" and "Lbs," respectively. By following this method, it is obvious that one card will provide four characters 36 and that the number of cards necessary to be 5 carried in stock in order to give the maximum range of characters or numbers will be materially reduced since each card may be used to display four characters or numbers. It is to be understood that this type 10 of card is used in combination with a price card such as 25 in the preferred form of the invention and that the two cards when retained in display position will be similar in appearance to the two cards shown in the 15 preferred form of the invention illustrated in Figure 1.

The cards are formed from relatively stiff cardboard or paper and the tabs when positioned over the lower card, as shown in Figure 2, will be sufficient to retain the two cards against movement relative to each other and insure of their occupying at all times their proper relative position and thus providing a neat appearing price marker 25 which is capable of display upon the shelves of a store in which the articles are offered for sale.

Having thus described the invention, what is claimed is:

- 30 1. A price display system comprising two cards adapted for use in combination with each other, printed matter upon each of said cards which when the cards are used together forms a portion of a complete readable legend, and a plurality of tabs formed in one of said cards, one edge of one of said cards being adapted to underlie one or both

of said tabs to retain the cards together, and both of said tabs carrying printed matter to be employed in combination with the printed matter of said cards to form a complete readable legend. 40

2. A price display system comprising a card, having a character or characters associated therewith, a second card having a 45 character or characters associated therewith, and means comprising a plurality of tabs formed integrally with one of said cards and adapted to singly or together overlie the edge of another of said cards to retain the 50 two cards in overlapped position, and characters carried by said tabs and adapted when read in combination with the characters carried by the cards to form a complete readable legend. 55

3. As an article of manufacture, a card, characters associated therewith, a plurality of tabs formed in said card adjacent said characters, said tabs having characters thereon, a second card adapted for secure- 60 ment to the first mentioned card by having one of its edges positioned beneath one of said tabs and in a position to obscure the other of said tabs, and characters associated with the second mentioned card 65 whereby a complete legend including the characters of the first mentioned card, the displayed tab and the second mentioned card will be had when two of said cards are positioned in superimposed relation. 70

Signed at New York, New York, this 28th day of May, 1925.

HERMANN HOPP.
LEO HOPP.
